DOOR LOCK CONSTRUCTION

George W. Wells, Amesbury, Mass., assignor to
 Harley C. Loney Company, Detroit, Mich., a
 corporation of Michigan

Application February 3, 1939, Serial No. 254,443

1 Claim. (Cl. 292—223)

This invention relates to door locks for automotive vehicles, having particular reference to the latch mechanism in which the keeper yields to the bolt upon door closure as distinguishable from constructions in which the bolt is retracted by the striker plate upon closure.

The object of the invention is to construct an inexpensive latch characterized by its simplicity of construction and installation and the ease with which a door equipped with the present invention may be opened and closed. The latch of the invention combines novel latch mechanism used in combination with a novel form of striker plate. The latch mechanism embodying a retractable bolt comprises a relatively small number of inexpensive sheet metal parts, as compared with similar devices now in commercial use, and is so designed as to enable the same to be mounted on the outside along the outer edge of the swinging door. The novel striker plate is designed for installation in door frames in the manner of striker plates now being used commercially on automotive vehicles and embodies a one-way acting clutch, which freely yields to admit the latch bolt yet prevents removal of the latch bolt from engagement therewith except upon retraction. A suitable mechanism is provided on the interior of the door of the vehicle so that the latch may be operated from the inside of the vehicle when in one position and function to prevent operation of the latch from the outside when in another position.

In the drawing,

Fig. 1 is a cross-sectional view through a door and door frame showing the latch mechanism in plan,

Fig. 2 is a side elevational view of the latch mechanism with a section of the door broken away, with a portion of the latch mechanism shown in section taken on lines II—II of Figs. 1 and 3,

Fig. 3 is a view of the striker plate assembly as viewed on the section III—III of Fig. 2, in the direction indicated by the arrows, and

Fig. 4 is a sectional view of a modified bolt having a latch for holding the same projected.

Referring to the drawing, in Fig. 1 the reference character 10 designates a swinging door of an automobile of usual construction having an outer panel 12, an inner panel 14, and an edge panel 16 adjacent the door frame 18 carrying the striker plate. An outside door handle 20 of usual construction is supported in the panel 12, with the rotated shaft 22 thereof extending through a suitable opening and being supported at its inner

ends in a bracket 24. The shaft 22 is square to receive an arm 25 having a pin 26 at its upper end passing through a slot 28 in a U-shaped bracket 30.

5 In the panel 16 an elongated opening 31 is provided to receive the latch mechanism, which embodies a mounting plate 32 constituting a cover plate for the opening 31 and having upper and lower ends 34 and 36 secured to the panel 16 by screws 38 or other suitable fastening means. The 10 bolt 40 is carried by the upper end of an elongated plate 42, having at its lower end feet 44 extending through openings 46 in the plate 32. There is sufficient clearance in the openings 46 to enable the plate 42 to swing about the feet 44 to retract and project the bolt 40 through the opening 48 in the plate 32. Shoulder cap screws 50 are threaded into the plate 32 at 52 and pass through openings 54 in the plate 42 with sufficient clearance to permit the plate 42 to pivot around its feet 44. Springs 56 located between the head of the screws 50 and acting against the plate 42 function to project the bolt 40, acting to urge the plate 42 at all times toward the position 15 shown in Fig. 2. A suitable spring (not shown) rotates the outside handle 20 back into its normal position urging the arm 25 against the limit pin 57 on the bracket 24 following rotation to open the door. As should be readily understood, 20 rotation of the shaft 22 of the outside handle 20 counter-clockwise, as viewed in Fig. 2, will cause the pin 26, through its engagement with one end of the elongated slot 28, to rock the plate 42 about its feet 44 through the U-shaped plate 30.

35 The striker plate comprises a suitable sheet metal casing 60 having flange portions 62 and 64 for supporting the same in a suitable recess 66 located in the door frame 18 in a well known manner. The outer face 68 of the casing 60 has 40 an opening 70 therein with an aligned opening 72 and a front side 74 of the casing. When the door 10 is swung closed, the bolt 40 passes through the opening 72, with the underside 76 sliding upon and supported by the door supporting surface 45 78 of the striker plate. The approach 80 of the surface 78 is preferably slightly sloped downwardly, and the leading edge of the bolt 40 is slightly sloped upwardly as at 82, as more clearly shown in Fig. 3, so as to take care of any slight 50 misalignment or sagging of the door that may exist. The door support action of the surface 78 exerted through the bolt 40 as well as the clamping action of the keeper, as will be hereinafter described, holds the door from up and down movement, thus doing away with the usual dove-

tails. The keeper 84 is preferably fabricated of some hard, wear-resisting nonmetallic material, such as, for example, a condensation product reinforced with fabric. As shown, the keeper 84 is pivotally supported upon a pin or stud 86 and continuously urged to the position shown in Fig. 1 by a spring 88. The face 90 of the keeper 84, which engages with the bolt 40, progressively increases in distance from the axis of the pin 86 from its front portion 92 to its rear portion 94. The surface 90 also has a transverse slope, as more clearly shown in Fig. 2, in the direction of bolt projection.

To specifically describe the construction of the bolt 40 so that its cooperation with the keeper 84 will be clearly understood, the upper surface of the bolt 40 has two longitudinally spaced sloping portions or lobes 98 and 100, the surface portions of which correspond generally to the operative surface 90 of the keeper 84. Preferably, the engaging surfaces of the bolt with the keeper have a slope corresponding generally to that of the surface 90 of the keeper. With this arrangement, should a person close the door 10, retaining the handle 20 in a position retracting the bolt 40, upon releasing the handle 20, through the action of the spring 56 the bolt 40 would be projected to the position shown in Fig. 2 and into locking engagement with the keeper 84.

The operation of my improved door lock and the cooperation between the bolt 40 and the keeper 84 is as follows: When the door 10 is closed, with the bolt 40 in a projected position, the leading edge 102 of the bolt 40 will engage with the leading edge 92 of the keeper 84 to rock the latter clockwise, as viewed in Fig. 3, so as to enable the same to seat upon the slope portion 98. Now it is in safety catch position, and the door cannot open for the reason that an opening movement of the door with the bolt 40 projecting would necessitate counter-clockwise movement of the keeper 84, which is impossible due to the shape of the keeper 84 and the fact that the bolt 40 is rigidly supported for sliding movement in a horizontal plane upon the supporting surface 78. Upon the movement of the bolt 40 from a safety catch position into that position shown in Fig. 3, in which the door is fully closed, this will result in the keeper 84 being again rocked counter-clockwise due to engagement of the leading edge 92, with the projecting surface 104 and the movement thereafter of the keeper 84 into the position shown in Fig. 3, in which the surface 90 of the keeper 84 is engaging with the slope 100 of the bolt 40. With the bolt 40 and the keeper 84 in the position shown in Fig. 3, any opening movement of the door 10 is resisted by the fact that this would necessitate a counter-clockwise movement of the keeper 84, which cannot take place because of the shape of the surface 90, the presence of the bolt 40, and the resistance of the supporting surface 78. Although the spring 88 is relatively light, with the result that the keeper 84 will yield to the bolt 40 under the slightest pressure with relatively silent closing of the door, due to the gradual pitch of the surface 90 this light spring pressure is sufficient to continuously urge the door into a snugly closed position.

It will become apparent from a consideration of Fig. 2 that the bolt 40 must be substantially retracted relative to the striker plate before being released by the keeper 84. This arrangement prevents the movement of the bolt from its fully closed position to the safety catch position upon

partial retraction of the bolt, as is possible in a great many locks now being used upon automobile doors, and to a great extent eliminates any practical necessity for the provision of a safety catch position in the locking structure.

As heretofore stated, the design of the bolt 40 and the keeper 84 is such that the bolt 40 can move into locking engagement with the keeper 84 either by transverse movement or axial movement, the transverse movement taking place when the door is closed with the bolt retracted and thereafter released, and the axial movement taking place when the door is closed with the bolt in a projected position, engagement taking place in either case in either the safety latch or the fully locked position.

For operating the bolt 40 from inside of the door 10, the side 106 of the bracket 30 is slotted at 108 to receive a pin 110 carried by the arm 112, which is in turn pinned at 114 to the plate 116 upon the shaft 118 of the inside handle 120. The mounting bracket 122 has an extension 124 with a flange 126 slotted at 130 to receive the arm 112. The arm 112 is reduced at 132 to receive a spring 134, which abuts the flange 126 at one end and the collar 136 at the other. With the handle 120 in the full line position of Fig. 2, the pin 110 is at one end of the slot, with the linkage formed by the arm 112 and plate 116 in a straight line. With the parts in this position, retraction of the bolt 40 by the outside handle 20 is prevented. With the handle 120 in the dotted line position, the pin 110 is at the opposite end of the slot 108, and counter-clockwise movement will rock the plate 42 and the bolt 40 carried thereby to retract the bolt, permitting the door 10 to be opened. When the handle 20 is turned to retract the bolt 40 with the inside handle 120 in the dotted line position, the pin 110 merely traverses the length of the slot 108.

It will be apparent to those skilled in the art that the door latch construction herein disclosed for the most part may be inexpensively fabricated from sheet metal parts. The striker plate, as well as the latch mechanism supported in the door, is adapted for installation in the present type of construction for automobile doors and does not necessitate any material changes. My improved construction is considered to have very definite advantages over that disclosed in my Patent No. 2,090,493, granted August 17, 1937. In the present construction the bolt is positively retracted in a conventional manner to clear the keeper. Moreover, the bolt is provided with at least one, and preferably two, very definite projections, which engage behind the keeper to provide a very positive latching action between the bolt and the keeper. This is particularly so where the rigid supporting surface is provided beneath the keeper and against which the action of the keeper clamps the bolt.

It will be understood that the safety catch or latch projection on the bolt may be omitted. However, at the present time this feature is considered desirable in automobile doors. It is anticipated within the scope of the present invention to rotate the keeper through a 90° plane from that disclosed and to consistently alter the relative action of the bolt, in which case the bolt would be projected and retracted in the plane of the edge of the door to clear the keeper. The pivotal movement of the keeper will take place in a horizontal plane.

In Fig. 4, the bolt 40' is shown equipped with a latch 138 pivoted at 140 in a slot 142. A spring

144 urges the latch 138 into the position shown preventing the bolt 40' from being retracted when the door is opened. When the door is closed the supporting surface 78 will rock the latch 138 upwardly to clear the flange 48' to permit the bolt 40' to be retracted. This arrangement assures the projecting of the bolt at the time of door closure preventing the door from being closed with the bolt retracted except under the circumstances where the bolt is retracted to open the door and held in that position upon door closure.

Having thus described my invention, what I desire to protect by Letters Patent and claim is:

In a latch for automobile doors, the combination of a bolt supporting structure, a retractible bolt supported from said structure and having a safety catch projection and a full latch projection upon the upper surface thereof, a striker

plate having an opening therein to receive and bolt, said opening being defined in part by a supporting surface for supporting and guiding the under side of said bolt, a keeper pivotally supported in said striker plate above said supporting surface and spaced therefrom, a spring urging said keeper into said opening into the path of said bolt, said keeper yielding to entering movement of said bolt into said opening, a portion of the under side of said keeper having cam shape and progressively increasing in radial displacement from the pivotal axis of said keeper, said portion engaging with either of said projections to prevent movement of said bolt in an opposite direction and acting to clamp said bolt against said supporting surface, and means for retracting said bolt to clear said keeper.

GEORGE W. WELLS.
